BY *M. M. Leo*,
ATTORNEYS

UNITED STATES PATENT OFFICE.

LOESER KALINA, OF NEW YORK, N. Y.

WOMAN'S GARMENT.

1,313,697.

Specification of Letters Patent.

Patented Aug. 19, 1919.

Application filed December 17, 1918. Serial No. 267,131.

To all whom it may concern:

Be it known that I, LOESER KALINA, a citizen of the United States, and a resident of the city of New York, borough of Brooklyn, 5 in the county of Kings and State of New York, have invented new and useful Improvements in Women's Garments, of which the following is a full, clear, and exact description.

10 The object of the invention is to provide certain new and useful improvements in women's dresses and gowns whereby the lining when soiled or injured can be quickly removed from the garment and cleaned and replaced, or replaced by a new one, without requiring any changes in the construction of the garment. Another object is to permit an accurate fitting of the lining to the wearer's body without altering the garment or buying a garment of a different size. Another 15 object is to permit the user to readily change the sleeves together with the lining if desired. Another object is to enable the manufacturer to provide a number of interchangeable sleeves of different materials for each garment; for instance, sleeves made of Georgette for summer wear or satin sleeves for use with the garment in winter.

With these and other objects in view the 20 invention consists of certain novel features of construction as hereinafter shown and described and then specifically pointed out in the claims.

A practical embodiment of the invention 25 is represented in the accompanying drawings forming a part of this specification, in which similar characters of reference indicate corresponding parts in all the views.

Figure 1 is a perspective view of the lining 30 detached from the garment and with parts shown in section;

Fig. 2 is an enlarged sectional front elevation of the garment;

Fig. 3 is a front elevation of a modified 45 form of the lining;

Fig. 4 is an enlarged sectional plan view of the lining illustrated in Fig. 3 in position in the dress;

Fig. 5 is a perspective view of another 50 modified form of the lining;

Fig. 6 is an enlarged elevation of the attaching means for detachably connecting the lining with the dress at the waist line; and

Fig. 7 is a sectional plan view of the same. 55 The dress or gown provided with the im-

provements and as shown in Fig. 2 comprises a skirt 10, a waist 11, sleeves 12 attached to sleeve bands 13 extending within the waist 11 and detachably connected with a lining 14 for the waist 11. The lining 14 60 illustrated in Figs. 1, 2, 6 and 7 is provided at the armholes with bands 20 provided with perforations 21 engaged by lacing strings 22 engaging perforate bands 23 secured inferiorly to the sleeve bands 13 of the sleeves 65 12. Thus by the arrangement described the sleeves 12 are detachably fastened by the perforate bands 20 and 23 and the lacing strings 22 to the lining 14. It is understood that the bands 20 and 23 are annular and 70 encircle the lining 14 and the sleeve bands at the armholes to permit of securely but detachably connecting the sleeves to the lining.

It is understood that the lining 14 75 follows the shape of the waist 11 of the garment and varies according to the type of the waist. It is also understood that if the waist opens at the front the lining likewise opens at the front as shown in Figs. 1, 3 and 5, but 80 should the waist 11 open at the back the lining will likewise open at the back. The lining 14 is provided at the lower edge of the waist line with a band 30 having spaced perforations 31 engaged by a lacing string 32 85 also engaging perforations 33 formed along the upper edge of a band 34 secured at its lower edge by stitches 35 to the dress or gown at the waist line thereof, as will be readily understood by reference to Fig. 2, see also 90 Figs. 6 and 7. It will also be noticed that by the arrangement described the lining 14 is detachably connected with the sleeves 12 and with the garment at the waist line to 95 permit of readily removing the said lining from the garment whenever such lining is soiled and needs cleaning. It will further be noticed that the lining after being cleaned can be readily re-attached to the garment or a new lining may be attached to the garment 100 by the use of the lacing strings 22 and 32 engaging the corresponding perforate bands 20, 23 and 30, 34. It will further be noticed that interchangeable sleeves of different material can be readily fastened to the lining 105 or detached therefrom thus permitting a manufacturer to provide a number of interchangeable sleeves of different materials for each garment. Thus sleeves made of Georgette or similar light fabrics and provided 110

with sleeve bands 13 of a stronger material can be attached to the lining for summer wear of the garment, while satin sleeves may be attached to the lining for use of the garment in winter.

I do not limit myself to the means shown and described for detachably connecting the lining with the sleeves of the waist 11 as the same may be varied, for instance as shown in Figs. 3 and 4, the lining 40 is provided with perforate bands 41 extending from the front lower end of the lining over the shoulder to the rear lower end thereof, and these bands 41 are connected by lacing strings 42 with perforate bands 43 attached to the inside of the waist 44 and overlying the bands 41, as plainly shown in Fig. 4. The lining 40 is provided at its lower end with a perforate waist line band 45 detachably connected by a lacing string 46 with a perforate band 47 attached to the garment at the waist line thereof and corresponding to the band 34 previously described and shown in Figs. 1, 2, 6 and 7.

The connections between the lining and waist may be at other points than the ones mentioned; for instance, as shown in Fig. 5, the lining 50 is provided at the neck opening 51 with a perforate band 52 adapted to be connected by a lacing string with a similar band on the neck opening of the waist of the garment. The lining 50 is provided at its lower or waist line edge with a perforate band 52 similar to the bands 30 and 45 and adapted to be fastened by a lacing string to a perforate band such as the bands 34 and 47 attached to the garment at the waist line, as previously explained.

From the foregoing it will be seen that I do not limit myself to the detachable connection of the lining to the waist at any particular point as the same may be varied without deviating from my invention.

It will be noticed that by the arrangement described the lining when soiled or injured can be quickly removed from the garment, cleaned and replaced, or replaced by a new one without requiring any changes in the construction of the garment. It will also be noticed that by the use of the lacing strings and perforate bands any desired adjustment may be made to accurately fit the lining to the wearer's body without altering

the dress or buying a garment of a different size.

Having thus described my invention, I claim as new and desire to secure by Letters Patent:

1. In a garment, an outer dress having a skirt and a waist, a perforate attaching member fixed on the dress at the waist line, a lining provided at the waist line with a perforate attaching member, a lacing string connecting the said waist line attaching members with each other, co-acting attaching members fixed on the said waist and the said lining at points other than the waist line, and a lacing string connecting the said last mentioned co-acting attaching members with each other.

2. In a garment, an outer dress having a skirt and a waist provided with separate sleeves, a lining, lacing, means detachably connecting the said lining and dress together at the waist line, and lacing means detachably connecting the said lining and sleeves together.

3. In a garment, an outer waist having separate sleeves, a lining for the waist, perforate bands at the armholes of the said sleeves and lining, and lacing strings detachably connecting the said bands with each other.

4. In a garment, an outer waist having perforate bands, a lining provided with perforate bands, and lacing strings detachably connecting the said bands with each other.

5. In a garment, an outer dress having a skirt and a waist provided with sleeves, a lining, coacting perforate bands at the waist line of the said dress and lining, lacing strings detachably connecting the said bands with each other, co-acting perforate bands at the armholes of the said sleeves and lining, and lacing strings detachably connecting the said armhole bands with each other.

6. In a garment, an outer sleeveless waist, a lining means detachably connecting the lining with the waist, and sleeves for the waist and attached to the lining.

7. In a garment, an outer waist having armholes, sleeves separate from the waist and extending through the armholes, and a lining detachably fastened to the waist and on which the sleeves are secured.

LOESER KALINA.
